UNITED STATES PATENT OFFICE.

GEORGE C. CONDITO, OF WINGDALE, NEW YORK.

LIFTING-JACK.

1,345,135.

Specification of Letters Patent. Patented June 29, 1920.

Application filed January 14, 1919. Serial No. 271,072.

To all whom it may concern:

Be it known that I, GEORGE C. CONDITO, a citizen of the United States, residing at Wingdale, in the county of Dutchess and 5 State of New York, have invented new and useful Improvements in Lifting-Jacks, of which the following is a specification.

This invention relates to new and useful improvements in lifting jacks, and pertains 10 more particularly to lifting jacks of the screw type which are adapted to be hand operated.

The primary object of the invention is to provide a hand operated lifting jack in 15 which means is provided to operate the same in either direction to raise and lower the lifting element at the will of the operator.

A further object of the invention is to provide means for locking the actuating 20 mechanism in either of its operative positions.

A further object of the invention is to provide a device of this character which is both simple and cheap in construction, and 25 of easy operation.

With the above and other objects in view which will appear as the description of the case proceeds, reference is had to the accompanying drawings in which:—

30 Figure 1 is a top plan view of a jack constructed in accordance with the present invention.

Fig. 2 is a side elevation thereof.

Fig. 3 is a longitudinal sectional view 35 through the jack.

Fig. 4 is a detail view of one of the lifting elements.

Fig. 5 is a sectional view on the line 5—5 of Fig. 4.

40 Fig. 6 is a fragmentary view partly in section of the spider member and the pawl actuating means.

Fig. 7 is a detail sectional view on the line 7—7 of Fig. 6.

45 Fig. 8 is a detail view in top plan of the pawl engaging disk.

Fig. 9 is a transverse section through the pawl engaging disk.

Fig. 10 is a detail view of the retaining 50 nut for the pawl engaging disk.

Fig. 11, is a detail view in elevation of that portion of the jack shown in Fig. 10, and

55 Fig. 12, is a detail view of the operating mechanism locking means.

Referring more particularly to the draw-

ings, the reference character 10 designates the pedestal of the jack, said pedestal being provided with an enlarged base 11.

This pedestal member 10 is substantially 60 hollow, and has its upper end reduced as at 12, said reduced end being provided with an internal screw thread 13. The pedestal 10 is also provided with a cut out portion or slot 14, the purpose of which will be here- 65 inafter described, and near its upper end at a point substantially diametrically opposite the slot 14 the pedestal 10 is provided with a handle 15.

Having screw threaded engagement with 70 the internal screw thread of the pedestal 10 and movable longitudinally thereof is a screw threaded standard 16, the thread of said standard being designated by the numeral 17. The screw thread 17 terminates 75 at a point remote from the lower end of the standard 16 to provide a smooth bearing surface 18, while the extreme lower end of the screw threaded standard 16, is provided with a screw thread 19. 80

Mounted on the smooth bearing surface 18, is a lifting element 20 which projects through the slot 14, and on its under face, and concentric with the opening 21 in which the smooth bearing surface 18 operates, this 85 lifting element is provided with a ball race 22.

Threaded on the screw threaded end 19 of the standard 16 is a nut 23 which is shown in Figs. 3, 10 and 11, and is provided on its 90 upper face 24 with a concentric ball race 25. This nut 23 is also provided with a transversely extending opening 26 which is screw threaded as at 27 for the reception of a transversely extending locking pin or bolt 95 28 which serves to secure the nut 23 against accidental displacement. The upper face of the lifting element 20 is roughened or serrated as shown at 29, and on its under face it is provided with an integral lug or the 100 like 30. Mounted between the lifting element 20 and the nut 23 in the ball races 22 and 25 are balls 31 which serve to form an anti-friction joint between the lifting element 20 and the nut 23. 105

Mounted on the upper end of the standard 16 is a shoe or the like 32, the upper face of which is roughened or serrated as shown at 33, and mounted between the upper end of the standard 16 and the shoe 32 is a ball 34 110 for the purpose of reducing friction between these two members, and said shoe 32 is re-

tained on the upper end of the standard 16 by means of the screw 35.

Near its upper end, the screw threaded standard 16 is provided with an annular 5 collar 36 above which the standard 16 is squared as at 37, and mounted on the collar 36 and having a squared central perforation 38 for the reception of the squared portion 37 of the standard 16 is a disk 39. This 10 disk is secured in place by means of set screws or the like 40.

This disk 39 is provided with a plurality of equi-distantly spaced perforations 41 which extend entirely through the disk and 15 are arranged near the edge thereof, the bottoms of these recesses being closed by means of a plate 42 secured in place by bolts 43.

Mounted for rotation about the standard 16 and resting on the upper face of the disk 20 39 is a spider or similar member 44 which is provided with a plurality of perforations 45 so spaced as to be adapted for movement into register with the perforations 41 in the disk 39, and mounted for vertical sliding 25 movement within these perforations 45 are pawls 46 which are provided on their upper end with an off-set portion 47. The perforations 45 are provided with extensions 48 for the reception of the off-set portion of said 30 pawls. These pawls 46 are provided on their lower ends with inclined faces 49, and said pawls are arranged in sets with the inclined faces of one set disposed in one direction, and those of the other set arranged in 35 the opposite direction.

The spider member 44 is cut out as to form an annular channel 50 and mounted for rotation in said channel is a ring 51 which is provided throughout a portion of 40 its periphery with a head 52 adapted to be received within an annular passage 53 in the upper surface of the spider member.

The spider member 44 also is provided with a hollow extension 54 which is adapted 45 to receive an operating handle 55 shown in dotted lines in Fig. 3. Pivotaly mounted on the top of said hollow extension is a lever 56, provided on one end with a handle 57. The inner end of this lever 56 is adapted to 50 engage in a recess in the ring 51 so that when the lever is rocked the ring 51 is rotated in the annular channel of the spider member 44.

This ring 51 is provided on its under face with cut out portions 59, one wall of which 55 is provided with a projection 60 which is adapted to engage the under face of the head 47 of its respective pawl, the head of the pawl being received in said cut out portion 59.

60 From the foregoing, it will be seen that if the spider member 44 is rocked about the standard 16 in one direction, that one of the sets of pawls will be lifted out of the openings 41 in the disk 39 in which they are en-

gaged, and if the lever is actuated in the opposite direction, the other set of pawls will be likewise operated.

As shown in Fig. 7, the set of pawls which are disengaged from the openings 41 are held up in their disengaged positions by 70 the shoulders 60 formed in the recesses 59, and these several shoulders are moved into and out of engagement with their respective pawls by means of the ring member 51, which in turn is operated by the pivoted lever 56, which is held in either of its positions by means of a spring pressed pin 60, which is actuated by means of the coil spring 61. This pin 60 and spring 61 are mounted 75 in a recessed lug 62, and retained therein 80 by means of the hollow screw 63.

From the foregoing, it will be seen that the present invention provides novel means by which the screw threaded standard 16 may be rotated in either direction to raise or 85 lower either of the lifting elements 20 and 32.

Having thus described the invention, what is claimed is:

1. A lifting jack comprising a pedestal, a 90 lifting screw threadedly connected with the pedestal, a disk fixed to the screw and provided with an annular series of apertures, a spider member free to rotate on the screw above the disk and provided with sets of 95 movable pawls adapted to co-act with the apertures in said disk to respectively revolve the screw in two directions, means adapted to revolve upon the spider member, said means co-acting with the pawls and adapted 100 to control their movements with respect to the apertures in said disk, mechanism for actuating said means, and a shoe carried by said screw.

2. A lifting jack comprising a pedestal, a 105 lifting screw threadedly connected with the pedestal, a disk fixed to the screw and provided with an annular series of apertures, a spider member free to rotate on the screw above the disk and provided with sets of 110 movable pawls adapted to co-act with the apertures in said disk to respectively revolve the screw in two directions, means adapted to revolve upon the spider member, said means co-acting with the pawls and adapted 115 to control their movements with respect to the apertures in said disk, mechanism for actuating said means, a shoe carried by said screw, and a locking device engageable with the actuating mechanism, as and for the 120 purpose described.

3. A lifting jack comprising a pedestal, a screw threadedly connected with said pedestal, a disk fixed to the screw to rotate therewith and provided with an annular series of 125 apertures, a spider free to revolve on the screw and disposed above the disk, sets of pawls movable vertically in the spider and

adapted to co-act with the apertures in said disk, movable means concentric of the screw for respectively actuating said sets of pawls with relation to the apertures in said disk,
5 an operating handle carried by the spider, mechanism for actuating the movable means,

and a locking device co-acting with said mechanism to retain adjustments of the movable means.

In testimony whereof I have affixed my 10
signature.

GEORGE C. CONDITO.
